E. A. PETERSON

PIPE WRENCH

Filed Feb. 9, 1922

Inventor
Ernest Aaron Peterson.

By Harry Q. Schroeder
Attorney

UNITED STATES PATENT OFFICE.

ERNEST AARON PETERSON, OF OAKLAND, CALIFORNIA.

PIPE WRENCH.

Application filed February 9, 1922. Serial No. 535,234.

To all whom it may concern:

Be it known that I, ERNEST AARON PETERSON, a citizen of the United States, residing at Oakland, in the county of Alameda and State of California, have invented certain new and useful Improvements in Pipe Wrenches, of which the following is a specification.

My invention is an improved pipe wrench 10 of simple and durable construction, which may be easily and quickly adjusted or released.

Referring to the annexed drawing in which my invention is illustrated and which 15 forms a part of this specification:

Figure 1 is a side view of my wrench.

Figure 2 is a front edge view of my wrench.

Figure 3 is a longitudinal section of the 20 slide.

In the drawing 1 indicates a shank; 2 a fixed jaw at one end of said shank; and 3 a handle at the other end of said shank. The jaw 2 has a concaved toothed engaging surface 4. A slide 5 is slidably mounted on the shank 1, which slide includes a pair of side walls 6 and 7 which fit against the sides of said shank, a rear wall 8 which is located adjacent the back edge of said shank, and a 25 block 9 which fits between the lower portion of said side walls adjacent the front edge of said shank and is secured to said side walls by rivets 10 and 11, the rivet 10 being larger than the rivet 11 and extending 30 through the block near its rear and upper edges and the rivet 11 extending through the block near its lower forward corner. From the inner edge of the block 9 near its lower edge projects a stud 12 for engaging 35 sockets 13, 14, 15 and 16 respectively in the shank 1, and the back wall 8 of the slide 5 is inclined backwardly from the upper to the lower edge of the slide, so that the slide 40 may be swung forwardly from the pivot point where the wall 8 engages the back of

the shank 1 to disengage the stud 12 from any of said sockets, whereby the slide is released and allowed to be moved along the shank. A flat spring 17 is secured at its upper end to the upper part of the inside 50 of the slide rear wall 8 and its lower part engages the back of the shank 1 and normally holds the slide with its stud 12 in engagement with one of the sockets 13, 14, 15 or 16, whereby the slide is detachably held 55 in different positions on the shank.

A jaw 20 is pivoted between the upper forward corners of the slide side walls 5 and 6 by a pivot 21 which extends through said jaw and said side walls at said corners. 60 Said jaw has a convexed toothed engaging surface 22 which cooperates with the concave toothed engaging surface 4 of jaw 2 in gripping a pipe. The jaw 20 may be swung on its pivot 21 into different positions to 65 engage the pipe in conjunction with the jaw 2.

Having described my invention, I claim:

A pipe wrench including a shank, a fixed jaw on one end of said shank formed with a 70 concaved toothed engaging surface, a handle on the other end of said shank, said shank having a plurality of sockets along its forward edge, a slide on said shank, a stud on said slide for engaging any of said 75 sockets, the rear wall of said slide inclining from the back edge of said shank opposite said stud so that said slide may be swung to cause said stud to engage or disengage any of said sockets, a spring between said 80 back wall of said slide and the back edge of said shank for normally holding said stud in one of said sockets, and a jaw pivoted in said slide formed with a convexed tooth engaging surface cooperating with the 85 concaved toothed engaging surface of said fixed jaw.

In testimony whereof I affix my signature.

ERNEST AARON PETERSON.
